US00D804525S

(12) **United States Design Patent** (10) Patent No.: **US D804,525 S**
Clarke et al. (45) Date of Patent: ** Dec. 5, 2017

(54) **DISPLAY SCREEN OR PORTION THEREOF
WITH GRAPHICAL USER INTERFACE**

(71) Applicant: **Apple Inc.**, Cupertino, CA (US)

(72) Inventors: **Graham Clarke**, Mountain View, CA (US); **Paulo Michaelo Lopez**, Los Gatos, CA (US); **Johnnie Manzari**, San Francisco, CA (US); **Britt Miura**, Menlo Park, CA (US); **Henrique Penha**, San Francisco, CA (US)

(73) Assignee: **Apple Inc.**, Cupertino, CA (US)

(**) Term: **15 Years**

(21) Appl. No.: **29/590,919**

(22) Filed: **Jan. 13, 2017**

Related U.S. Application Data

(63) Continuation of application No. 29/560,706, filed on Apr. 8, 2016, now Pat. No. Des. 776,711, which is a continuation of application No. 29/492,616, filed on Jun. 1, 2014, now Pat. No. Des. 753,678.

(57) **CLAIM**

The ornamental design for a display screen or portion thereof with graphical user interface, as shown and described.

DESCRIPTION

The FIGURE is a front view of a display screen or portion thereof with graphical user interface.

The outermost broken lines in the FIGURE show a display screen or portion thereof, and form no part of the claimed design. The other broken lines in the FIGURE show portions of the graphical user interface that form no part of the claimed design.

The dot-dash broken lines in the FIGURE and the area within the dot-dash broken lines show portions of the graphical user interface that form no part of the claimed design.

1 Claim, 1 Drawing Sheet
